Patented Feb. 15, 1916.

THE COLUMBIA PLANOGRAPH CO., WASHINGTON, D. C.

UNITED STATES PATENT OFFICE.

GUSTAV BAER, OF NEW YORK, N. Y.

MATERNITY-SKIRT.

1,172,102.

Specification of Letters Patent. Patented Feb. 15, 1916.

Application filed June 26, 1915. Serial No. 36,563.

To all whom it may concern:

Be it known that I, GUSTAV BAER, a citizen of the United States, and a resident of New York, in the county of New York and State of New York, have invented certain new and useful Improvements in Maternity-Skirts, of which the following is a specification.

My invention relates to dress skirts for women in a pregnant condition, and the main object thereof is to provide a skirt the style or appearance of which is unaltered during the entire period of pregnancy despite the gradually enlarged adjustment thereof in the progressive stages of pregnancy.

In skirts of this class now known to me it is necessary to alter the appearance to meet the progressive conditions, either by the gradual enlargement of plaits or by destroying the location of certain arrangements of the fabric and thus destroying the original balanced effect of the skirt, or for other reasons, and it was in order to overcome this that my invention was conceived.

My invention is fully described in the following specification, of which the accompanying drawings form a part, in which like characters refer to like parts in each of the views, and in which:—

Figure 1 is a front view of one style of skirt made in accordance with my invention; Fig. 2 is a rear view thereof; Fig. 3 is a perspective view of the upper portion of the skirt, in position as worn; Fig. 4 is a similar view in open position; Fig. 5 is an enlarged section taken on the line 5—5 of Fig. 3; and Fig. 6 is a section taken on the line 6—6 of Fig. 5.

In the drawings forming a part of this application I have shown one type of skirt consisting of two members 7 and 8, the former of which is the skirt proper and the latter the belt therefor, each forming a part of the skirt as an entirety. The member 7 is shown as provided with front and rear exterior panels 9 and 10, respectively, arranged centrally of the body of the wearer and draped to meet the required fullness at the lower edge 11 of the member 7; when the skirt is made with these panels thus centrally arranged, it is desirable to maintain the same in these positions, and of the same widths, during the development of the pregnant state, in order to not alter the original appearance of the skirt; although these

panels are shown as centrally arranged, I do not confine myself to such positions, nor indeed to a panel effect necessarily, as I will conform the skirts to the prevalent styles as far as possible.

The belt member 8 is formed of a strip folded longitudinally to form two dependent portions 12 and 13, the former of which is provided with tapes 14 at its ends, and with one member 15 of each of a plurality of fasteners arranged on each side of the center of the length of said portion 12, five being shown in each group in Fig. 4, but the number of which may be varied as desired. The portion 13 is intended to be worn in full view and may be made of any desired design, being shown as with rounded ends 16, buttons 17 adjacent to said ends, and button-holes 18 at the rear thereof, one being shown on each side of the center of the length thereof, to receive the respective ones of two buttons 19 carried by the skirt member 7 at the upper end of the panel 10. The panel 9 is secured to the body of the skirt member 7 at one of its edges, the other edge being free to form a placket and being provided with one member 20 of each of a plurality of fastening devices adapted to engage with the other respective member 21 of the fasteners secured to the skirt member at the edge of the placket. It will be seen that this panel 9 does not vary in its appearance under any conditions, nor does the panel 10, as will now be shown. The back panel 10 is formed by folding the fabric inwardly to form a fold 22, the fabric being stitched together as shown at 23 in Fig. 5 to insure permanency of the panel 10, said fold 22 being provided at each side of the central line of the skirt and being extended inwardly to approximately the center line of the skirt and the fabric is again folded outwardly on lines 24; the stitching 23 holds the panel portions of the fabric in panel formation, as does also the stitches or threads used in sewing on the buttons 19.

The inner side of the waist band 25 is provided with a plurality of complementary members 26 of the fasteners the other members 15 of which are carried by the belt member 8, these fastener members 26 being arranged on each side of the center line of the skirt and being spaced, in each group, to conform to the spacing of the members 15, but more members 26 are provided than of the members 15 of the fasteners; these fas-

teners may be of the glove fastener type, hooks and eyes, buttons and button-holes, etc. etc., or any suitable equivalent therefor.

When the skirt is worn by a normal woman the folds 22 are of maximum length, and the fastener members 15 are connected with the respective members 26 for this adjustment of the length of the waist-band 25, now at its minimum length. The skirt 5 may now be put on and taken off by connecting and disconnecting the free edge of the panel 9 from the body of the skirt, the portion 12 of the belt 8 being arranged inwardly of the waist-band 25 and the 10 tapes 14 tied and untied to connect or disconnect the belt with the body of the wearer, the portion 13 of said belt being arranged exteriorly of the waist-band 25 to conceal the same, and the tapes 14 being 15 concealed beneath the panel 9. As the development advances, the fastener members 15 may be disconnected from the members 26 to which they had been connected, on each 20 side of the central line of the skirt, and again connected with the next successive respective fasteners 26, thus lengthening the 25 waist-band 25 to an extent equaling the distance between the fastener members 26 on each side of the central line of the skirt. 30 This step by step lengthening of the waist-band may be repeated as occasion requires until the last fastener member 26 is reached on each side of the skirt, but no effect is 35 produced upon either panel nor any effect upon the appearance of the skirt, the only difference being the increase in distance between the respective edges of the two panels, but this is not apparent to the observer. The belt 8 accommodates itself to this development by reason of the tapes 14, but its 40 relationship with the skirt at its points of buttoned connection at the rear of the skirt remains unchanged. A slight change is

apparent at the front of the belt by reason of the gradual separation of the ends of the 45 belt, but this is hardly noticeable and, if desired, a new and larger belt may be provided for the extreme conditions without in any way affecting the skirt.

The particular style is subject to change 50 and modification to meet the whims of the wearers and to conform to the conventionalities, my main intent being to provide means for adjusting the skirt to gradually changing conditions without any change in 55 the appearance thereof.

With a reservation of all such changes as come within the scope of my invention and of the following claim, my invention consists of a skirt having fixed characteristics of 60 style, a separable belt therefor, and means for adjustably connecting the skirt with the belt.

Having fully described my invention, what I claim as new, and desire to secure by Letters Patent, is:—

A skirt having its upper edge at the rear folded inwardly and then outwardly on each side of the center line of the skirt to form a panel, a plurality of fastener members disposed horizontally on the inner face of each 70 folded portion, a belt-like member secured to the upper edge of the skirt and depending within the same, the belt-like member being disconnected at the front from the skirt and provided with means for varying its length, 75 and fastener members disposed horizontally on the outer surface of the belt-like member and adapted to mate with the first named fastener members.

In testimony whereof I have signed my 80 name to this specification in the presence of two subscribing witnesses.

GUSTAV BAER.
